BRAKE SHOE CONSTRUCTION

Robert J. Burrows and Alfred O. Williams, Battle Creek, Mich., assignors to Clark Equipment Company, Buchanan, Mich., a corporation of Michigan

Application May 12, 1936, Serial No. 79,315

9 Claims. (Cl. 188—230)

This invention relates to brake shoe constructions, and more particularly is directed to the mounting of a brake shoe on a brake supporting head for movement toward and away from the associated surface to be braked.

It has been customary heretofore to mount brake shoes of the segment type, which are adapted to cooperate with the tread portions of the wheels of vehicles such as rail cars and the like, by means of a brake shoe key on a supporting head. The supporting head in such instances is carried on a brake beam which moves the head and shoe bodily toward and away from the tread surface of the wheel. This results in arcuate movement of the brake surface of the shoe and tends to produce unequal wear on this surface. Also, with such constructions, the key is of necessity formed as a tapered wedge member, and adjustment is made by driving up the key. Looseness between the parts results in rattling and wear.

It is the primary object of the present invention to mount the brake shoe on a pivot pin carried by the brake head, whereby the shoe has pivotal movement into and out of engagement with the surface with which it is associated. This tends to equalize the contact of the shoe against the brake surface so that uniform wear of the shoe surface is produced.

Another object of the present invention is to provide resilient means engaging the lateral surface of the shoe to produce frictional pressure engagement thereon which prevents rattling of the shoe with respect to the supporting head, and at the same time frictionally holds the shoe in approximate operative position.

Still another feature provided by the present invention is the provision of take-up means, whereby upon predetermined wear of the braking surface on the shoe, the pivotal support of the shoe with respect to the arm or supporting head can be changed to take up this wear and results in proper braking effort being applied with the same movement of the supporting head.

Another object of the present invention is to provide stop means for limiting rotation of the shoe about its pivotal support in order to maintain it in proper operating position.

Other objects and advantages of the present construction will be more apparent from the following detailed description which, taken in conjunction with the accompanying drawing, will disclose to those skilled in the art the construction and operation of a preferred form of the present invention.

In the drawing:

Figure 1 is a side elevational view of the brake shoe and supporting head; and

Figure 2 is an end elevational view, partly in section, of the assembly shown in Figure 1.

Referring now to the drawing in detail, we have disclosed a brake shoe, indicated generally at 5, having the arcuate reinforced portion 6 provided at its outer edge with the tapered brake surface 1 which is adapted to engage the corresponding tapered rim portion of a car wheel or the like. The shoe 5 is provided with reinforcing rib portions 8 which terminate at the rear end of the shoe in the thickened bosses 9 and 10. Intermediate the reinforcing ribs 8, the shoe is provided with the boss portion 12 which extends coplanar with the defining surfaces of the bosses 9 and 10 and projects forwardly thereof.

A brake supporting head 15 is provided having the cylindrical collar portion 16 engaging about the external surface of an operating rock shaft 17 which extends through the collar 16 and is connected to any suitable operating brake mechanism. The head 15 is provided with a bifurcated arm portion 18 having the parallel extending arms 19 and 20 which are spaced apart a distance such as to receive therebetween the boss portions 9 and 10 of the shoe 5.

The arm 19 is provided with the laterally offset portion 22 which terminates in spaced bosses 23 and 24 disposed in alignment with the boss portions 9 and 10 of the shoe 5. Each of the bosses 23 and 24 is provided with an axially extending bore 25 which is adapted to receive the coiled spring 26 biased between the friction plate 27 and a spring follower 28 which is threaded into an enlarged portion of the bore 25. The follower 28 in each of the bores is provided with a reduced projecting stud 29 which centers the outer end of the spring 25, while the friction plates 27 are provided with extending finger portions 30 which center the inner end of the spring with respect thereto. These friction plates on their inner face surfaces bear against the lateral surfaces of the boss portions 9 and 10 of the shoe 5, holding the shoe against rattling between the arms 19 and 20 and also serving as friction elements to support the shoe against rocking movement with respect to the supporting head 15.

The head 15 adjacent the collar portion 16 is provided with a normally extending offset 32 threaded to receive the stop pin 33 threaded therein into a position such that the head of the pin engages the lower portion of the brake shoe 5 to hold it in a position extending sub-

stantially at right angles to the head 15. The pin 33 is provided with a lock nut 34 to hold it in any desired fixed position with respect to the offset 32.

5 The boss portion 12 of the shoe 5 is disposed between the forwardly extending portions 35 of the arms 19 and 20, and is pivotally supported therebetween by means of the pin 36 which extends through suitable openings in the portions 35 10 of the arms and through a corresponding opening in the boss portion 12 of the shoe. The pin is held in position by means of the cotter key 31.

It will be noted that the shoe 5 between the boss portions 9 and 10 thereof has a second opening 38 extending laterally therethrough which is disposed rearwardly of aligned openings 39 formed in each of the arms 19 and 20 intermediate the bosses 23 and 24. When the surface 7 of the shoe 5 wears down to any considerable extent, it will be obvious that in order to produce braking pressure, the head 15 must be rotated to a greater extent about the center of the shaft 17. As this condition occurs, it becomes necessary to take up for this wear, and this is accommodated by removing the pin 36 from the position shown in Figures 1 and 2, moving the shoe 5 forwardly to align the openings 38 and 39 and then inserting the pin 36 into these aligned openings. Due to the fact that the openings 38 and 39 are offset with respect to each other in the initial position of the shoe, it will be apparent that as the surface 7 wears down and the shoe is moved forwardly to bring these openings into alignment, the shoe will be positioned 35 substantially the same relative engagement with the head 15, the centers of the openings 38 and 39 being spaced apart a distance slightly less than the equivalent wear of the shoe which can be accommodated before such take-up is necessary.

It will be apparent that by the present construction we provide a brake shoe pivotally supported on a brake head with friction means resiliently pressed against lateral surfaces on the shoe to prevent the shoe from rattling with respect to the brake head and to hold the shoe against free swinging movement about its pivotal support. Also, by reason of the single pivotal mounting of the shoe, it is obvious that the shoe 5 can shift or rock about its pivot so that the brake surface 7 has full equalized braking contact with respect to the associated wheel, the shoe being free to accommodate itself to this position during the arcuate movement of the head 15. Also, the adjustable stop pin prevents the shoe from falling out of operative position with respect to the head or moving into cocked engagement with the wheel surface.

60 It is to be understood that the spring followers 28 may be made adjustable in order to vary the pressure on the friction plates 27 if so desired, or they can be removed and new springs inserted whenever desired. Also, it is to be understood that the spacing between the center of the bosses 35 of the arms 19 and 20 and the centers of the openings 38 and 39 can be varied to meet different conditions encountered in practice.

We do not intend to be limited to the specific 70 construction which we have shown and described, inasmuch as various equivalent means may be employed for accomplishing the same purpose. The invention is therefore to be limited only as defined by the scope and spirit of the appended 75 claims.

We claim:

1. In combination, a brake shoe, a supporting head therefor having a bifurcated arm receiving said shoe, a pin extending through said arm and shoe pivotally supporting said shoe on said arm, means on said head preventing rotation of said shoe in one direction, spaced bosses on one arm of said head on opposite sides of said pin, resilient means carried in each of said bosses and engaging the lateral surface of said shoe between said arms for preventing vibration of said shoe with respect to said head, and means threading into said bosses for retaining said resilient means in pressure engagement with said shoe surface.

2. A brake shoe construction comprising a supporting head having a bifurcated arm portion, a brake shoe having a boss portion received within said bifurcated arm portion, a pin pivotally supporting said shoe on said head, and means carried by one arm portion of said head on opposite sides of said pin engaging the lateral surface of said boss portion for frictionally holding said shoe in position relative to said head, said means being accessible from one side of said head independently of the pivotal support of said shoe.

3. In combination, a brake shoe having a pair of pin receiving openings therein, a brake head having a bifurcated arm portion receiving said shoe and having a pair of pin receiving openings spaced apart a distance less than the openings in said shoe, and pin means carried by said arm and adapted to extend through either of said pair of openings to support said shoe for pivotal movement on said arm, said arm having means normally urged into frictional engagement with the lateral surface of said shoe to hold said shoe in position with respect to said arm while accommodating slight pivotal movement thereof.

4. In combination, a brake shoe having a pair of spaced pin receiving openings, a brake arm adapted to support said shoe and having a pair of pin receiving openings spaced apart a distance different than the spacing of said shoe openings, a pin adapted to extend through either pair of openings for supporting said shoe pivotally on said head, and friction means normally holding the shoe in position with respect to said head but permitting pivotal movement of said shoe with respect to said head during braking engagement of said shoe.

5. A brake shoe construction comprising a brake supporting head having a pair of spaced normally extending bosses, a brake shoe carried by said head, means pivotally mounting said shoe on said head intermediate said bosses, friction plates carried by said bosses and engaging the lateral surface of said shoe on opposite sides of said pin, and spring means normally urging said friction plates into pressure engagement with said surfaces.

6. In combination, a rock shaft, a brake arm supported for conjoint movement with said shaft and having a pair of spaced arm portions, a brake shoe having a boss received within said arm portions, a pivot pin carried by said arm portions and engaging said shoe for pivotally supporting said shoe on said arm, means for shifting the point of pivotal support of said shoe with respect to said arm, and friction means on one side of one of said arm portions and engaging said shoe for normally maintaining said shoe in position with respect to said arm.

7. A supporting head for a brake shoe comprising a pair of parallelly extending arm portions adapted to receive the web of the brake shoe.

therebetween, one of said arm portions having spaced normally extending threaded bosses, friction means in the inner end of said bosses engaging the lateral web surface of said shoe, spring means in said bosses biased at one end against said friction means, and closure means threaded into the outer end of said bosses and engaging the opposite ends of said spring means.

5 8. The head specified in claim 7 characterized by a series of pivot pin openings in said arm portions between said bosses and extending in a direction normal to a line passing through said bosses.

10 9. A supporting head for a brake shoe, comprising a hub portion adapted to be mounted on

an operating shaft, a pair of radially extending axially spaced arms adapted to receive the web of a brake shoe therebetween, a series of pivot pin openings in said arms for receiving a pin pivotally supporting said shoe therebetween, spaced 5 normally extending bosses on one of said arms adapted to contain resilient friction means engaging one lateral surface of the web of said shoe upon opposite sides of the pivot pin support therefor, and an integral normally extending lug adjacent said hub including means for limiting rotation of said shoe in one direction with respect to said head.
